METAL WINDOW, DOOR, AND THE LIKE

Emanuel Gray, New York, N. Y., assignor of one-half to Raymond B. Shoemaker, Flushing, N. Y.

Application April 5, 1938, Serial No. 200,061

6 Claims. (Cl. 189—65)

This invention relates to windows and doors, especially those of the metal casement type, and has for its object to provide a simple and weather-tight construction.

5 Another object is to provide a window or door which is self aligning or centering on being closed.

In the practical art difficulty is encountered in making casement windows and the like satisfactorily wind and weather tight. One reason is believed to be due to the fact that the weather-stripping has been generally exposed when the window is open with the result that it may become accidentally deformed in part or moved 10 out of position by the person who opens and closes the window. Another difficulty has been due to the weather-stripping being compressed more in some parts than in others. Especially is this true if the frame is canted or tilted by the building sagging in one direction.

20 Referring to the drawing—

Fig. 1 illustrates a form of a stationary frame with pivotal closure partly open.

Fig. 2 is a view corresponding to Fig. 1 but with 25 the window closed.

Fig. 3 is an elevation partly in section showing the internal packing applied to a double hung or sliding type sash.

Fig. 4 is a detail in section of the vertical 30 weather-stripping for the double hung sash of Fig. 3.

In Figs. 1 and 2 the wall 30 has a stationary supporting frame 31 to which is secured the frame 33 which contains the internal weather-stripping. Plaster 32 or other customary finishing is provided on the inside of the building wall 30 and screws 34 secure the frames 31 and 33 together. The head of the screws 34 may be covered over with grout or other cementitious material. The frame 33 carries hinge supporting elements 35 to which the movable hinge member 36 is pivotally secured at 37, the movable frame member 38 being carried by the closure supporting member 36. Window glass or any suitable panel 39 is held in place between some yieldable packing means 39a and a metal clamping strip 40 which holds the glass in place as indicated. This strip may be deformable for ease in insertion. Around all four sides of the closure frame 38 is a channel 41 of arcuate cross section within which is received the weatherstrip 42 of sponge rubber or equivalent material. The same type weather-stripping is placed in the stationary frame 33 as illustrated.

55 Beside the weatherstrip 42 each of the frame

members 33 and 38 is provided with a rib 43 adapted to engage and deform the tubular weatherstrip as the window or door is closed. This rib 43 is shaped to engage the internal weatherstrip 42 in each frame member at an angle to the general plane of the frame members and press the projecting portion of the tubular weatherstripping inwardly into its channel, deforming the weatherstrip as shown in Fig. 2.

5 This same general type of tubular weatherstripping is illustrated in Fig. 3 applied to a double hung or slideable sash in which the stationary frame member 44 is provided with the internal tubular weatherstrip 49 and the movable frame member 45 is similarly provided with such internal weatherstripping.

The internal weatherstripping in both the movable and stationary frame members is received within a channel 48 of arcuate cross section as illustrated. On each side of the weatherstripping in each of the frame members is a longitudinal rib 50 of generally curved cross sectional contour but adapted to function in a manner similar to that shown for the ribs 43 in Figs. 1 and 2. That is, these ribs 50 and 43 are adapted to make the movable frame member self-aligning in closing. In each embodiment of this invention these ribs extend at an angle to the plane of the frame members and engage the weatherstripping in the cooperative frame member in a 20 generally edgewise manner, although in Figs. 3 and 4 the edgewise cooperation of the rib with the packing strip is less pronounced than is the case in the preceding embodiments illustrated.

The movable frame members vertically cooperate with the stationary frame member 44 as shown in Fig. 4 and in order to provide additional means for holding the movable frame members tightly in engagement with the stationary frame member there may be provided screw actuated 30 or adjustable roller means 47. Instead of the roller pressure means 47 some appropriate form of adjustable wedging device may be used.

It will also be understood that any type of rib 43 or 50 illustrated, may be used for cooperation with the internal weatherstrip of a cooperating frame member. The function of the longitudinal rib to align and properly close the movable frame member is believed to be of advantage regardless of whether the movable frame member 50 be mounted for pivotal or sliding travel. As previously mentioned the frame members of Figs. 1 to 4 inclusive may be made by any of the methods described and these frame members may be tubular or somewhat solid as indicated.

From the drawing it may be seen the movable frame of this invention is adapted to be centered by movement in either direction parallel to the general plane of the frame members when closed and also by movement of the movable frame member substantially normal to the plane of the stationary frame member. An inclined or cam surface forming less than 45° with any of these directions of movement aids in this centering movement. Another feature is the cutting away of a portion of the rigid cam surfaces at the vertex of a pair of adjacent cam surfaces which form an angle of less than 180°, not only to provide space for an internal weatherstrip, which need not be necessarily used, but also in case the cooperative cam surfaces do not precisely abut, more of an opportunity for an interfitting movement is provided by removal of a part of a limiting abutment at the vertex.

20 The term "exposed side" occurring in the claims is not intended to imply that the frame members may be only of polygonal shape.

I claim:

1. Stationary and movable frame members for 25 a wall opening, each having on its face adjacent the other frame member and on its exposed sides at least three guide surfaces adapted to abut cooperative surfaces on the other frame member when the movable frame member is 30 closed, two of said guide surfaces on each frame member being at a larger acute angle to the plane of the frame member than is the guide surface intermediate said two.

2. A closure for a wall opening having fixed 35 and movable frame members at least one of which has on its face adjacent the other frame member and on its exposed sides, an internal weather-strip on each side of which is a cam surface, the other of said members having a rib with an edge 40 formed by two cam surfaces each forming an acute angle to the planes of said frame members when closed, at least one of the rib cam surfaces being adapted to engage one of the cam surfaces of the member having the weather-strip to assist in positioning the movable member in closing, the cam surfaces of one member substantially abutting the cam surfaces of the other member when the movable member is closed and the edge of said rib engaging and deforming said strip.

50 3. A closure for a wall opening having fixed and movable frame members, each of said frame members having on one face thereof and on each exposed side, at least two cam surfaces which substantially abut the complementary cam sur-

faces of the other frame member, one pair of abutting cam surfaces forming an angle of less than 45° with the general plane of the frame members when in closed position and the other pair of abutting cam surfaces forming an angle 5 of substantially more than 45° with the general plane of the frame members.

4. A closure for a wall opening having fixed and movable frame members, each frame member having on one face and on each exposed side, a 10 plurality of cam surfaces which are adapted to engage cooperative cam surfaces on the other frame member and being so arranged that relative movement between said frame members either in the direction of their plane or substantially normal thereto tends to center the movable frame member into closed position by engagement with a cam surface forming an angle of not more than 45° with the direction of said movements.

5. A closure for a wall opening having fixed 20 and movable members each of which has on at least one face thereof and on each exposed side a pair of adjacent cam surfaces adapted to cooperate with cam surfaces on the other member to assist in centering the closure, said cam surfaces forming an angle of less than 180° to one another on one member and more than 180° on the other, and each surface forming an acute angle to the plane of the members when closed, the vertex of said adjacent cam surfaces forming 30 an angle less than 180° being cut away in at least one of the members to remove a portion of a rigid limit in width of each cam surface in event the cooperative cam surfaces may not abut throughout their full area.

6. A closure for a wall opening comprising fixed and movable members one of which has on at least one face thereof on each exposed side a pair of adjacent cam surfaces adapted to abut cooperative cam surfaces on the other member to assist in centering the closure, said pair of cam surfaces on one member forming an angle of less than 180° and on the other member the cooperative surfaces forming an angle greater than 180°, one cooperative or abutting pair of cam surfaces forming an angle of not more than 45° to the general plane of said members and the other pair of abutting cam surfaces forming an angle of not less than 45° to the plane of said members, the vertex of the adjacent cam surfaces forming less than 180° being cut away to remove a portion of a rigid limit in width of each cam surface in event the cooperative surfaces may not fully abut.

EMANUEL GRAY.
